UNITED STATES PATENT OFFICE.

CHARLES F. PECKHAM, OF PROVIDENCE, RHODE ISLAND.

AUTOMATIC SPRINKLER.

1,259,663.

Specification of Letters Patent. Patented Mar. 19, 1918.

Application filed June 8, 1917. Serial No. 173,480.

To all whom it may concern:

Be it known that I, CHARLES F. PECKHAM, a citizen of the United States, residing at Providence, in the county of Providence and State of Rhode Island, have invented 5 certain new and useful Improvements in Automatic Sprinklers; and I do hereby declare the following to be a full, clear, and exact description of the invention, such as 10 will enable others skilled in the art to which it appertains to make and use the same.

The invention relates to sprinkler heads such as are used in automatic fire extinguisher systems.

15 The object of the invention is to provide novel and improved valve holding and releasing means which will operate in a uniformly reliable manner in releasing the valve, and the holding efficiency of which 20 will not be impaired by long continued use. To these ends the invention comprises the features of construction and the combinations of parts hereinafter described and referred to in the claims, the advantages of 25 which will be readily understood by those skilled in the art from the following detailed description of a head embodying the invention in its preferred form and shown in the accompanying drawings.

30 In the drawings Figure 1 is an elevation of a sprinkler head embodying a preferred form of the invention; and Fig. 2 is a sectional elevation on line 2—2 of Fig. 1.

As shown, the sprinkler head comprises 35 a nozzle 2 screw threaded at 4 for attachment to a distributing pipe, and also screw threaded at 6 for the adjustment thereon of the yoke shaped frame 8. The delivery end of the nozzle is closed by a valve cap 10 40 which is held to its seat by a collapsible strut interposed between the valve and an abutment 12 on the frame. The frame carries a distributor 14 of usual construction.

The valve holding strut comprises a lever 45 16 engaging the abutment 12, a post 18, the upper end of which engages the short arm of the lever and the lower end of which engages the valve cap, a second lever 20 underlying and supporting the long arm of the 50 lever 16, and a brace 22 interposed between a shoulder 24 on the post and a shoulder 26 on the outer end of the lever 20. The levers 16 and 20 are held from movement lengthwise of each other by a lug 28 on the lever 55 16 which engages a recess 30 in the lever 20. The superposed levers, post and brace form

a strut interposed between the valve and frame, the parts of which will collapse under the pressure applied to the valve unless they are held or locked in holding relation, since the pressure on the post and lever 16 tends to rock the levers 16 and 20 away from each other until the lug 28 and recess 30 are disengaged, when the members of the strut are free to fly apart. The parts 60 of the strut are normally held or locked by a rod 32, the lower end of which is provided with a spherical enlargement forming a shoulder 34 for sustaining the inner end of the lever 20, the end of the rod being held 65 against lateral movement by the face of the post 18, no part of which falls within an arc described by the outer surface of the enlargement with the extremity of the lever 16 as a center. The rod extends out through 70 a hole in the upper end of the frame 8 and is provided at its outer end with a head 36 sustained by the fusible metal of a thermal fuse arranged outside the frame. The fuse comprises a hollow cylinder 38 of metal 75 which will fuse at a comparatively low temperature and commonly termed in this art a "fusible" metal. The cylinder of fusible metal may be and preferably is inclosed in a heat-conducting and non-corrosive shell 40. 80 85

With this construction the parts of the strut are effectively held by a fusible metal located outside the strut where it will be quickly acted upon by the heat, and of such shape that it will not be liable to the cold 90 flow or defective action incident to constructions in which parts of the strut are united by the fusible metal. The locking means is also of such a character that sudden release of the valve upon the fusing of 95 the fusible metal is insured and all danger of a partial collapse of the strut due to release of water before the strut has been fully released, is avoided.

While it is preferred to employ the specific construction and arrangement of parts shown and described, it will be understood that this construction and arrangement is not essential to the broader features of the invention and may be varied and modified 100 without departing therefrom.

Having explained the nature and object of the invention, and specifically described one structure in which it may be embodied, what is claimed is:

110 1. An automatic sprinkler head having in combination, a valve, a frame, a collapsi-

- ble strut interposed between the valve and frame, a rod for resisting the collapse of the strut, and a thermal fuse sustaining the rod against endwise movement.
5. An automatic sprinkler head having, in combination, a valve, a frame, a collapsible strut interposed between the valve and frame, a fusible cylinder outside the frame, and a rod sustained by the cylinder and connected to the strut to resist its collapse.
10. An automatic sprinkler head having, in combination, a valve, a frame provided with an opposed abutment, a strut between the valve and abutment comprising a lever 15 engaging the abutment, a post between the lever and valve, a second lever underlying the first lever and connected therewith by an interlocking lug and recess, a brace between the second lever and post, and heat-controlled means preventing relative rocking 20 of the levers.
15. An automatic sprinkler head having, in combination, a valve, a frame provided with an opposed abutment, a strut between the valve and abutment comprising a post, a brace, and two superposed levers held from lengthwise movement by an interlocking lug and recess, a rod having its inner end between the inner end of the under lever and the face of the 25 post, and fusible metal sustaining the rod.
20. An automatic sprinkler head having, in combination, a valve, a frame provided with an opposed abutment, a strut between the valve and abutment comprising a post, a brace, and two superposed levers held from lengthwise movement by an interlocking lug and recess, a rod having a shoulder at its inner end for sustaining the inner end of the lower lever, and extending through the 30 frame, and a fusible cylinder outside the frame sustaining the rod.
25. An automatic sprinkler head having, in combination, a valve, a frame provided with an opposed abutment, a strut between the valve and abutment comprising a post, a brace, and two superposed levers held from lengthwise movement by an interlocking lug and recess, a rod having its inner end between the inner end of the under lever and the face of the 35 post, and fusible metal sustaining the rod.
30. An automatic sprinkler head having, in combination, a valve, a frame having an opposed abutment, a strut between the valve and frame comprising a post, a brace, and two superposed levers held from lengthwise movement by an interlocking lug and recess, a rod having its inner end between the inner end of the under lever and the face of the 40 post, and fusible metal sustaining the rod.
35. An automatic sprinkler head having, in combination, a valve, a frame having an opposed abutment, a strut between the valve and frame comprising a post, a brace, and two superposed levers held from lengthwise movement by an interlocking lug and recess, a rod having a shoulder at its inner end for sustaining the inner end of the lower lever, and extending through the 45 frame, and a fusible cylinder outside the frame sustaining the rod.
40. An automatic sprinkler head having, in combination, a valve, a frame having an opposed abutment, a strut between the valve and frame comprising a post, a brace, and two superposed levers held from lengthwise movement by an interlocking lug and recess, a rod having its inner end between the inner end of the under lever and the face of the 45 post, and fusible metal sustaining the rod.
45. An automatic sprinkler head having, in combination, a valve, a frame having an opposed abutment, a strut between the valve and frame comprising a post, a brace, and two superposed levers held from lengthwise movement by an interlocking lug and recess, a rod having a shoulder at its inner end for sustaining the inner end of the lower lever, and extending through the 50 frame, and a fusible cylinder outside the frame sustaining the rod.
50. An automatic sprinkler head having, in combination, a valve, a frame having an opposed abutment, a strut between the valve and frame comprising a post, a brace, and two superposed levers held from lengthwise movement by an interlocking lug and recess, a rod having its inner end between the inner end of the under lever and the face of the 55 post, and fusible metal sustaining the rod.
55. An automatic sprinkler head having, in combination, a valve, a frame having an opposed abutment, a strut between the valve and frame comprising a post, a brace, and two superposed levers held from lengthwise movement by an interlocking lug and recess, a rod having a shoulder at its inner end for sustaining the inner end of the lower lever, and extending through the frame, and a fusible cylinder outside the frame sustaining the rod.

CHARLES F. PECKHAM.
